UNITED STATES PATENT OFFICE

WILLIAM A. SCHOLLMAYER, OF YONKERS, NEW YORK

SHINGLE

Application filed February 12, 1929. Serial No. 339,368.

This invention relates to shingles and particularly composition shingles such as are formed of asphalt or asbestos.

Shingles of the type specified have a tendency, because of their flexibility, to blow up from the roof, thus admitting air beneath the shingles. Furthermore, when the shingles are blown up, rain and snow can gain access to the roof. It is customary, moreover, to lay shingles of the character specified in such a way that spaces are formed therebetween or between the exposed portions thereof. These spaces provide channels for the admission of air, rain or snow.

One of the objects of the invention is to provide a shingle structure so constructed and arranged that the shingles can be applied to a roof with a minimum amount of labor.

Another object of the invention is to provide a shingle that is simple and practical in construction, can be economically manufactured, and can be laid with speed and accuracy.

Another object of the invention is to provide a simple, practical and efficient clip for securing shingles in position.

Further objects of the invention will appear from the following specification taken in connection with the drawings, which form a part of this application, and in which

Fig. 1 is a plan view of a portion of a roof having secured thereto shingles constructed in accordance with the invention;

Fig. 2 is a view similar to Fig. 1 showing the same type of shingle laid in a different manner from that shown in Fig. 1;

Fig. 3 is a plan view illustrating the manner in which the shingles are cut from a blank or sheet of material;

Fig. 4 is a plan view of a single shingle constructed in accordance with the invention;

Fig. 5 is a view similar to Fig. 1 but illustrating the use of a shingle clip in securing the shingles in position;

Fig. 6 is a view similar to Fig. 2 showing the shingles secured by clips;

Fig. 7 is a plan view of a portion of a shingle showing the clip secured in position thereon;

Fig. 8 is a view taken at right angles to Fig. 7; and

Fig. 9 is a sectional elevation taken substantially on line 9—9 of Fig. 5.

The invention involves several novel features. A shingle constructed in accordance with the invention has a greater transverse dimension at one end than at the other, the end having the greater transverse dimension being provided with substantially parallel side edges. One of the side edges has an extension or tab projecting laterally therefrom. In laying the shingles they are placed side by side and the projecting tab engages and abuts against the parallel edge of the adjacent shingle, thus spacing the exposed portions of the parallel edges and simulating the appearance of a shingle roof. The end of the shingle having a lesser transverse dimension is preferably tapered and the shingles may be laid in such a way as to have rectangular exposed portions or hexagonal exposed portions.

Another feature of the invention involves the use of a clip adapted to aid in securing the shingles in position and to prevent the shingles from blowing up from the roof and to prevent air channels beneath the shingles. The clip is secured to the laterally projecting tab and is provided with tabs which extend beyond the upper and lower edges of the laterally projecting tabs. The lower tab on the clip is adapted to be bent over or around the lower end of a portion of a shingle of the next upper layer and the upper tab on the clip can be bent toward the roof to prevent or close air channels.

Further details of the invention will appear from the following description.

In the form of the invention illustrated in the drawings and particularly in Fig. 4, there is shown a shingle having one end portion 10 of greater transverse dimension than the other end portion 11. The end portion 10 is rectangular in shape and has substantially parallel side edges 14 and 15. One of the edges 14 has a laterally projecting extension or tab 20 at the inner end thereof, the tab having an outer edge 21 parallel to the edges 14 and 15.

The end 11 of the shingle has tapered side edges 25 and 26, these edges terminating at their inner ends at 27 and 28, the points 27 and 28 being spaced inwardly from the parallel edges 14 and 15 substantially equal distances. The outer edge 30 of the end portion 11 is flat and is parallel to the outer edge 31 of the other end portion 10. The shingle is so designed that the distance X between the edge 21 of the extension 20 and the point 27, plus the distance Y between the side edge 15 and the point 28, equals the width Z of the end 30 of the shingle.

Shingles of the form illustrated in Fig. 4 are cut from a strip or blank in the manner shown in Fig. 3 and it will be evident from the showing in this figure that there is very little waste involved in the cutting of the shingles.

Fig. 1 shows a shingle roof laid with shingles having the form of the shingle illustrated in Fig. 4 and it will be seen that the roof shown in Fig. 1 is laid in such a manner that the exposed portions of the shingles are rectangular.

In laying the roof illustrated in Fig. 1, the end portions 10 of the shingles in the lower layer are placed side by side on a straight line. The extension 21 of each shingle abuts against the parallel side 15 of the next adjacent shingle. The next row of shingles above the bottom row is laid with the shingles staggered with respect to the shingles of the lower row. In other words, the center lines of the shingles in the second row will be aligned with the spaces 35 between the end portions 10 of the shingles of the lower row. The third row will then be staggered in a similar manner with respect to the shingles of the second row. It will be noted that the shingles of the second, third, etc. rows are placed over the shingles of the rows beneath, a sufficient extent to cover the extensions 20 in the row beneath.

Fig. 2 illustrates a shingle roof also laid with shingles constructed as shown in Fig. 4, but laid in such a manner as to expose hexagonal portions of the shingles rather than rectangular portions thereof. In laying the roof illustrated in Fig. 2, the shingles are inverted or have the end portions 11 extending downwardly.

In the roof shown in Fig. 2, the extensions 20 serve to space adjacent shingles in the same manner as in Fig. 1. In order to lay the roof shown in Fig. 2, the shingles in the lower row are placed side by side, being spaced apart by the extensions 20 and having the ends 11 projecting downwardly. It will be seen that three-sided spaces 40 are formed between the downwardly projecting ends 11 of the lower row of shingles. The second row of shingles is laid in such a way that the downwardly extending ends 11 are positioned above the spaces 40 formed between the ends

11 of the lower row. In other words, the shingles in the second row are staggered with respect to the shingles of the lower row. It will be seen that the ends 11 of the shingles of the second row cover portions of the upper ends 10 of the shingles of the lower row and that the portions of the upper ends 10 which are exposed in conjunction with the portions 11 of the lower row of shingles, form an hexagonal figure. The third row of shingles is aligned with the first row and is staggered with respect to the second row.

From the foregoing description it will be seen that when the shingles having the construction illustrated in Fig. 4 are laid with their rectangular ends projecting downwardly, and the shingles in successive rows staggered, the exposed portions will be rectangular in shape. On the other hand, if the shingles are laid as shown in Fig. 2, with the tapered portions 11 projecting downwardly and with successive rows staggered, the exposed portions will be hexagonal in shape. In both cases the extensions 20 serve to accurately space and position the shingles.

Figs. 5 to 9 inclusive illustrate the use of a clip C for securing the shingles in position and closing air channels. The clip C is formed from a flat piece of material, preferably non-rustable metal, such as copper. The clip has a body portion 45 provided with end tabs 46 and 47. The body portion has substantially the same transverse and longitudinal dimensions as the corresponding dimensions of the extension 20 formed on the shingle, and the tabs 46 and 47 extend beyond the ends of the extension when the clip is secured in position thereon. The clip may be secured in any suitable manner and in the form of the invention shown, tabs 50 and 51 are punched out of the body portion 45 and are pointed so as to pierce and extend through the extension 20. After the tabs 50 and 51 are punched through the extension 20, they are bent back against the back surface of the extension, as shown in Fig. 8.

The clip C also has formed thereon a laterally projecting tab 54 having an opening 55 therein for receiving a nail or other securing means for the shingle. The tabs 46 and 47 are used to hold down the shingles of the succeeding upper rows and are also used to close air channels formed between the shingles.

Fig. 5 illustrates the form of roof shown in Fig. 1 and also shows the use of the clips C to hold down the lower ends of the shingles of the succeeding upper layers. It will be seen that the clips C carried by the extensions 20 of the shingles in the lower row have their tabs 47 bent around the lower ends 10 of the shingles in the next upper row or second row. Furthermore, the clips 46 are preferably bent downwardly against the roof to prevent the passage of air, although the

extensions 20 close the air channels between the edges of adjacent shingles.

In Fig. 6 the shingles are inverted as shown in Fig. 2 and in this case the tabs 46 are bent around the lower tapered ends 11 of the shingles of the next upper row. In other words, the lugs 46 carried by the extensions 20 of the lower row of shingles are bent around the edges 30 of the ends 11 of the next upper row. Again, the tabs 46 carried by the extensions 20 of the second row of shingles are bent around the lower ends 30 of the end portions 11 of the next upper or third row of shingles.

15 The tabs 54 of each shingle extend over the adjacent portions of the next adjacent shingle and a single nail driven through the opening 55 and tab 54 will secure both edges of the adjacent shingles in position.

20 From the foregoing description of the use of the clip C it will be evident that the clips, by reason of the tabs 46 and 47, materially assist in holding down the exposed portions of the shingles and also increase the speed 25 and accuracy with which the shingles can be laid.

Although certain specific embodiments of the invention have been particularly shown and described, it will be understood that the 30 invention is capable of modification and that changes in the construction and in the arrangement of the various cooperating parts may be made without departing from the spirit or scope of the invention, as expressed 35 in the following claims.

What I claim is:

1. A shingle having one end tapered in width and having substantially parallel side edges at the other end, and a tab projecting 40 laterally beyond one of the parallel edges and located at the inner end thereof, said tab being adapted to mount a securing clip.
2. A shingle having a straight side having a lateral extension, and a clip secured to said 45 extension, said clip having a portion projecting laterally beyond the extension and having end tabs extending substantially parallel to the longitudinal center line of the shingle.
3. A shingle having a straight side having a lateral extension, and a clip secured to said extension, said clip having a portion projecting laterally beyond the extension and having end tabs extending substantially parallel 50 to the longitudinal center line of the shingle, one of the tabs extending beyond the outline of the shingle.
4. A shingle having a straight side having an integral lateral extension, and a clip secured to said extension, said clip having a portion projecting laterally beyond the extension and having end tabs extending substantially parallel to the longitudinal center line of the shingle.
5. A shingle having parallel end edges,

one end portion having tapered edges converging to the end edge and the other end portion being rectangular, the tapered edges terminating at their inner ends nearer the longitudinal center line of the shingle than the side edges of the rectangular portion of the shingle, one of the side edges of the rectangular end portion having an extension extending laterally therefrom adapted to mount a securing clip.

6. A roof comprising a plurality of shingles, each having one end tapered and the other end provided with substantially straight parallel sides, one straight side of each shingle having a lateral extension engaging the other straight side of the other shingle whereby the adjacent straight sides of adjacent shingles will be spaced from each other, said extension being adapted to mount a securing clip for engagement with an adjacent shingle.
